[57] CLAIM

The ornamental design for a deployable mast and storage unit, substantially as shown and described.

DESCRIPTION

FIG. 1 is a perspective view of the deployable mast and storage unit showing in my new design with a portion of the mast deployed;

FIG. 2 is a perspective view thereof, showing the deployable mast in its stowed condition;

FIG. 3 is an enlarged top plan view thereof;

FIG. 4 is an enlarged right side elevational view thereof;

FIG. 5 is an enlarged left side elevational view thereof;

FIG. 6 is an enlarged bottom plan view thereof;

FIG. 7 is an enlarged front elevational view thereof; and

FIG. 8 is an enlarged rear elevational view thereof.
